UNITED STATES PATENT OFFICE.

THOMAS N. ATKINSON, OF ST. LOUIS, MISSOURI.

NECKTIE HOLDER AND FORMER.

1,253,457.

Specification of Letters Patent. Patented Jan. 15, 1918.

Application filed February 2, 1914, Serial No. 815,927. Renewed September 10, 1917. Serial No. 190,684.

To all whom it may concern:

Be it known that I, THOMAS N. ATKINSON, a citizen of the United States, and resident of St. Louis, State of Missouri, have 5 invented certain new and useful Improvements in Necktie Holders and Formers, of which the following is a specification.

This invention relates to improvements in a neck-tie holder and former, and has for 10 its object a plate having a curved slotted up portion, a recess in its body for the insertion of the collar button, and a loop located at the lower end through which the neck-tie is passed giving it the proper tying 15 effect.

A further object of my invention is to construct a device which is so shaped as to be supported on a collar button and over which the neck-tie is passed and held in a 20 properly formed condition; a portion of the device being properly ornamented to give the tie the stick-pin effect.

Figure 1, is a plan view showing the necktie over my improved device.

25 Fig. 2, is a perspective view of my invention viewing the same from the rear.

Fig. 3, is a vertical sectional view of the same.

Fig. 4, is a detail sectional view of the 30 upper portion of my device shown in position on the collar button.

In carrying out my invention I form my device preferably out of a sheet of material and in stamping the same I form a body 35 portion 5, in the shape of a key stone; and upper or flared portion 6, being slightly rounded and provided with an elongated slot 7. On the bottom or narrow end 8 I firmly secure a band or ring 9, on the front 40 of which may be placed an ornamental design 10; such as a signet, monogram, or in fact any kind of fanciful device or setting which would be ornamental and produce the stick pin effect.

45 In the body portion 5, I provide a pear shaped opening 11, adapted to receive the head and shank of a collar button, its upper end being small enough to prevent the passage of the head on the collar button 50 therethrough, and to the rear of the body I secure a spring 12, which is shaped to the exact contour of the elongated curved open-

ing, the said spring being partially compressed at the point indicated by the numeral 13 and the upper portion of the spring 55 extending back from the body portion 5. This elongated opening and the spring is for the purpose of permitting the device to be placed over the collar button 14, the spring having a tendency to press against 60 the collar and keep the front end of the device in firm position on the button.

The fabric which constitutes the neck-tie 15 is passed through the loop 9, and then up over the curved upper portion of the device and brought through the curved elongated opening 7, and this end is then brought down through the loop 9, in the rear of the front portion of the neck-tie. By this arrangement the tie retains a unique appearance 70 and the same can be readily and easily applied in position without causing the tie to be placed around the neck between or over the collar; and by means of the depressed portion of the spring the same will not be 75 removed from its position on the collar button except by pressing the device upwardly and forcing the depressed portion over the stem of the button.

Having fully described my invention 80 what I claim is:

A device of the class described comprising a body portion, having a curved upper portion of greater width than the main body portion in which is located an elongated 85 curved slot; a ring shaped band located at the bottom of the body portion upon which is located some ornamentation; a vertical pear-shaped opening formed in the body portion and above the ring shaped band; a 90 spring wire secured to the body portion and corresponding in shape with the opening formed in the body portion, the upper portion of the spring extending away from the body portion, in combination with a necktie 95 to be passed over the device and held thereon, substantially as specified.

In testimony whereof, I have signed my name to this specification, in presence of two subscribing witnesses.

THOMAS N. ATKINSON.
